METHOD AND APPARATUS FOR STRAIGHTENING METALLIC ARROWS AND THE LIKE

Harry Covy, 18615 Brentwood, Livonia, Mich.

Filed Aug. 1, 1957, Ser. No. 675,719

3 Claims. (Cl. 153—39)

This invention relates to metal arrows for use in archery, and relates specifically to a method and apparatus for straightening such arrows and the like which have become bent through use.

Archery is one of our oldest sports, but the use of metal arrows is comparatively new. Metal arrows are usually made of aluminum tubing, in order to be sufficiently light in weight. However, such arrows are very ductile, and are frequently bent when the target is missed, as the arrow strikes the ground or some other hard object. Obviously there is nothing so useless as a crooked arrow, and therefore they must be straightened before use.

The average archer either tries to straighten them himself by hand, with little success, or else takes them to some other person who straightens them by hand himself, also with little success except in obtaining a fee for each such effort. Some arrow shops use tool room methods for straightening arrows, but these are slow and costly, and obviously of no value in the field. What is really needed, therefore, is a method and apparatus for straightening arrows which will be fast, accurate, economical, and portable. That is the problem which this invention solves in a simple but novel way.

An object of the invention is thus to provide a method for straightening arrows, which is fast and accurate, and which can be used in the field.

A second object is to provide a novel gage for use in straightening arrows, in order to determine the straightness of an arrow at points along its length.

A third object is to provide an arrow straightener and gage which is accurate, economical, and portable.

An advantage of the invention is that it provides a method of straightening arrows which does not require skill or practice, which can be used in the field, and which is inexpensive.

Other objects and advantages of my invention will more fully appear in the accompanying description and drawings, wherein are disclosed preferred embodiments of my invention. In the drawings, like numerals refer to like parts.

In the drawings:

Fig. 1 represents an elevation, in cross-section, of a preferred embodiment of my invention;

Fig. 2 represents a plan view of said embodiment of my invention;

Fig. 3 represents a cross-section taken along the line 3—3 of Fig. 1; and

Fig. 4 represents a cross-section taken along the line 4—4 of Fig. 1.

In the drawings, a tubular metallic arrow 10, with point 11, fletching 12, and nock 13 is shown inserted in my arrow straightening apparatus, being held in position primarily by means of a bushing 14. Said bushing 14 is itself mounted in block 15, and held in position by means of a set screw 16. A round washer 17 is placed on the

2

end of the arrow, just beyond the nock 13 and before the fletching 12.

An alignment shaft 18 extends longitudinally from the bottom of said block 15. Its length is greater than the maximum distance which the arrow 10 can protrude rearwardly from said bushing 14. It is preferably fixed in position in said block 15 by means of a set screw 19. The longitudinal axes of bushing 14 and the alignment shaft 18 are substantially parallel to each other. At the end of said alignment shaft 18, I may provide a hook 20, for digging arrows out of sand in which they may have fallen during use.

Also mounted on said block 15 is a bending lever 21, with depending lugs 22, 23 abutting the sides of block 15, and being pivoted thereon by means of a pin 24 extending through said lugs 22, 23 and block 15. A straightening member 25 projects from said bending lever 21, on the opposite side of said lugs 22, 23, and is adapted to pass below said arrow 10. As shown in Figs. 1 and 2, said straightening member 25 may comprise a pair of arms 26, 27 adapted to pass around opposite sides of said arrow 10, and a connecting member 28 adapted to pass below said arrow 10 and to connect said arms 26, 27 to each other. Thus, the pin 24 acts as a fulcrum for the bending lever 21, so that when the latter is depressed, the straightening member 25, and in particular the connecting member 28 thereof, will be caused to exert an upward force on an arrow 10, thereby tending to bend it upwardly.

30 A handle 29 extending from said block 15, below said bending lever 21, assists in depressing the bending lever 21 by permitting a squeeze grip.

The upper surface of the block 15 contains an upwardly projecting boss 30. A threaded adjusting screw 31 extends through a threaded opening in the bending lever 21, in alignment with said boss 30. When the bending lever 21 is depressed, the boss 30 thus acts as a stop. The maximum amount of bending of an arrow 10 may therefore be adjusted by the extent to which the adjusting screw 31 has been screwed down toward the boss 30. A helical spring 32, held in position by said boss 30 and adjusting screw 31, acts to lift the bending lever 21 to its normal position after each use.

Another boss 33 also projects upwardly from the alignment shaft housing 34 which extends longitudinally from the lower part of block 15. A helical spring 35, the lower end of which is fastened to said boss 33, is adapted to extend up to the lower surface of the arrow 10 and to assist in keeping it in parallelism with the alignment shaft 18, in the event that there is a significant amount of play in the bushing 14.

The method of operation of my invention is as follows. The round washer 17 is placed over the nock 13 of an arrow 10 to be straightened, and the arrow 10 is inserted through the bushing 14 as far as it will go. The fletching 12 of the arrow 10 will thus be adjacent the straightening member 25, and an alignment gap 36 of about an eighth of an inch will exist between the washer 17 and the alignment shaft 18. The arrow 10 is now rotated by hand, and the alignment gap 36 is observed. If it varies during this rotation, e.g. if the washer 17 touches or substantially touches the alignment shaft 18 at any point during the rotation, the arrow 10 is bent. In order to straighten it, the arrow 10 is rotated to the position at which the alignment gap 36 is the minimum, indicating a bend downward toward the alignment shaft 18, and the bending lever 21 is depressed. The straightening member 25 will thus bend the arrow upwardly, to compensate for the downward bend. Proper adjustment of the adjusting screw 31 for a particular type of arrow 10 will limit the maximum amount of upward bending

of the arrow 10 to correspond to the difference between a normal alignment gap 36 (say $\frac{1}{4}$ inch) and no alignment gap whatever, i.e. to a downward bend of arrow 10 which is sufficient to cause the washer 17 to touch the alignment shaft 18. In the event a particular bend in the arrow 10 is less than this, the amount of upward bending of the arrow 10 will automatically be less than this when the bending lever 21 is depressed (as limited by the boss 30 and adjusting screw 31). If there is no bend whatever in the arrow 10 at a certain point, depression of the bending lever 21 in this way will cause no upward bending of the arrow 10.

To be more precise, if there is no bend in arrow 10 and the bending lever 21 is nevertheless depressed, the straightening member 25 exerts an upward stress on arrow 10 which does not exceed the elastic limit of the metal constituting said arrow 10, so that the arrow 10 is temporarily bent upward during operation of the bending lever 21 but upon release thereof, the arrow 10 springs back to its original configuration. This fact suggests the preferred method of adjusting the adjusting screw 31. For a particular type of arrow 10, pull said arrow 10 out of bushing 14 for most of its length, and find a position of the washer 17 which shows a normal alignment gap 36, so that no straightening is required at this point. The adjusting screw 31 should now be screwed in or out to such a position that the upward force which can be exerted by the straightening member 25 on the arrow 10 is substantially the maximum amount short of creating any permanent deformation or bending of the arrow 10. With such an adjustment of the adjusting screw 31, the amount of upward bending caused by depression of the bending lever 21 in any case will always be substantially the amount required to eliminate a downward bend in the arrow 10. Thus, no skill will be required in the bending operation as, regardless of the amount of straightening required, depression of the bending lever 21 will be sufficient to accomplish this result.

Thus, the existence of a bend at any point along the arrow 10 is discovered by rotating the arrow 10 to the point of minimum alignment gap 36. The bending lever 21 is then depressed, straightening out said bend. The arrow 10 is then pulled out of bushing 14 a little at a time, in each case rotating arrow 10 to check for bends by observing the alignment gap 36, until the entire arrow 10 has been straightened in this way.

In most cases, there will be only one bend, which will be readily found in this way, and readily corrected. If the bend is severe, it may be corrected by pulling the arrow 10 through the bushing 14 for its full length, while maintaining the bending lever 21 in the depressed position throughout.

In order to determine whether a particular arrow 10 requires any straightening at all, a quick check may be made by inserting said arrow 10 into the bushing 14 for only a short distance and rotating it, while observing the alignment gap 36. If no bend is noted in this way, it indicates that the arrow is straight from one end to the other, unless there should happen to be two exactly compensating bends, which is very rare, and which would normally be noticeable by eye.

An arrow straightener of this type weighs about one pound. The alignment shaft 18 can be unscrewed from its housing 34 and carried with the arrows, and the rest of the apparatus can be carried in the pocket of the quiver. Thus, the apparatus can be ready for use in less than a minute, and may be used in the field if desired.

Obviously, many variations in the details of construction of my invention are possible, and I shall not attempt to mention them exhaustively. Thus, instead of using a bushing 14 to hold the arrow 10 parallel to the alignment shaft 18, I may use a plurality of spaced, axially aligned bushings or V-blocks. I may provide for a variety of arrow diameters by using removable bushings or adapters. The details of the design of the straightening

member 25 may also be varied in many ways, for example by eliminating one of the arms 26, 27. In fact, the straightening member 25, lugs 22, 23, and bending lever 21 may be eliminated altogether, and the actual bending done by hand in the way described above, but this is not preferred because there is then no automatic determination of the correct amount of bending required.

Various other modifications may also be made without departing from the spirit of the invention as defined in the following claims which are directed to the principal features of the invention rather than to the readily changeable details.

I claim:

1. An apparatus for straightening shafts of metallic arrows and the like, comprising: a substantially straight alignment surface; longitudinal aligning means for rotatably and slidably holding said shaft substantially parallel to said alignment surface; a free annular round washer mountable transversely on and dismountable from said shaft, a substantially circular axial aperture extending therethrough of diameter large enough to permit sliding said washer over an end of said shaft for transverse mounting thereon but small enough to cause said washer when mounted on said shaft to fit tightly enough thereon to permit it to move linearly with and in rotation with said shaft as the latter moves, the outer radius of said washer being less than the distance between the longitudinal axis of said aligning means and the aforesaid alignment surface, so that a visually observable gap of predetermined magnitude is left therebetween in the case of a substantially straight shaft; and means for bending said shaft away from said alignment surface an amount sufficient to eliminate substantially any variation in the gap between said washer and said alignment surface when said shaft is rotated.

2. An apparatus for straightening shafts of metallic arrows and the like, comprising: a substantially straight alignment surface; longitudinal aligning means for rotatably and slidably holding said shaft substantially parallel to said alignment surface; a free annular round washer mountable transversely on and dismountable from said shaft, a substantially circular axial aperture extending therethrough of diameter large enough to permit sliding said washer over an end of said shaft for transverse mounting thereon but small enough to cause said washer when mounted on said shaft to fit tightly enough thereon to permit it to move linearly with and in rotation with said shaft as the latter moves, the outer radius of said washer being less than the distance between the longitudinal axis of said aligning means and the aforesaid alignment surface, so that a visually observable gap of predetermined magnitude is left therebetween in the case of a substantially straight shaft; a bending lever adapted to exert a force on said shaft to bend it away from said alignment surface an amount sufficient to eliminate substantially any variation in the gap between said washer and said alignment surface when said shaft is rotated; and an adjustable stop adapted to limit the maximum motion of said bending lever so that, in the case of a substantially straight shaft, said bending lever will exert substantially the maximum amount of force possible on said shaft without creating a permanent deformation thereof.

3. An apparatus for straightening shafts of metallic arrows and the like, comprising: a substantially straight alignment surface; a bearing and aligning block adapted for rotatably and slidably holding said shaft therein, substantially parallel to and spaced apart from said alignment surface; an annular round washer mounted transversely on an end of said shaft sufficiently tightly to move linearly and rotationally with said shaft as the latter is moved, the external radius of said washer being less than the distance between the longitudinal axis of said aligning block and said alignment surface; an alignment gap of predetermined magnitude, defined by the space between said washer and said alignment surface, said gap

being visually observable in the case of a substantially straight shaft; a bending lever adapted to exert a force on said shaft sufficient to bend it away from said alignment surface an amount sufficient to eliminate substantially any variation in said alignment gap when said shaft is rotated; and an adjustable stop adapted to limit the motion of said bending lever so that, in the case of a substantially straight shaft, said bending lever will exert substantially the maximum amount of force possible on said shaft without creating a permanent deformation thereof. 10
